UNITED STATES PATENT OFFICE

WARD T. BARKER, OF KANSAS CITY, MISSOURI

FURNACE

Application filed April 14, 1927. Serial No. 183,732.

My invention relates to furnaces and more particularly to structures of that character for use in connection with oil stills wherein it is desirable to maintain constant flow of a substantially large volume of hot gases at a uniform temperature in heating relation to the still.

Among the problems involved in the operation of furnaces of this type is the maintenance of a sufficient volume of circulating gases at the proper temperature for vaporizing contents of the still without overheating and without oxidation of the still tubes or jacket that would result from the presence of an excessive amount of oxygen in the heating medium. In accordance with my invention the volume of the medium is maintained with an economy of fuel by recirculating spent gases through the heating chamber with the addition of sufficient hot fresh products of combustion to maintain the proper temperature; the recirculating gases serving not only to provide the desired volume but further serving to dilute the oxygen which may pass through the combustion chamber as a result of incomplete combustion or oversupply of air in the fuel mixture.

It is, therefore, the object of my invention to provide a furnace structure wherein the spent gases may be recirculated through the heating chamber in proper combination with fresh products of combustion to maintain the constant flow and even working temperature with economy in fuel consumption and upkeep of structural elements.

In accomplishing this general object I not only provide for effective recirculation of the spent gases but further provide for delivery of the fuel elements in advantageous working condition by utilizing surplus gases for conditioning the fuel elements prior to their delivery to the combustion chamber.

In accomplishing these and other objects of the invention I have provided improved details of structure, the preferred forms of which are illustrated in the accompanying drawings wherein:

Fig. 1 is a sectional perspective view of a furnace embodying my improvements, illus-

trating its adaptability for use in connection with a tubular still.

Fig. 2 is a vertical, longitudinal section on the line 2—2, Fig. 4.

Fig. 3 is a vertical section on the line 3—3, Fig. 2.

Fig. 4 is a horizontal section on the line 4—4, Fig. 2.

Referring more in detail to the drawings:

1 and 2 designate side walls, 3 the front wall and 4 the rear wall of a furnace embodying my improvements and constructed in accordance with common practice in that they are lined with refractory brick or like material. 5 designates the furnace floor, preferably extending between the side walls from the front to the rear wall, and 6 a roof structure extending from the front of the furnace over the floor 5 to about midway of the structure and there merging into the offset portion 7 of the front wall, forming a throat 8 through which the portion 9 of the furnace, hereinafter referred to as the combustion chamber, communicates with the portion 10, hereinafter referred to as the heating or still chamber, the latter covered by a roof 11.

Located at the forward end of and extending transversely across the combustion chamber, at about the vertical center thereof, is an arch 12, supported near its forward edge from the floor 5 by a checkered work 13, forming a chamber 14 at the front end of the combustion chamber. The chamber 14 is preferably divided by a vertical wall 15 to form separate compartments, each covered by an arched roof section (12), which extends forwardly of a corresponding checkered work portion (13) to form a chamber 16 opening to the front end of the combustion chamber 9.

Extending transversely below the chamber 14 is a passageway 17 having communication with the compartments of said chamber through ports 17' in the furnace floor. Opening to each end of the passageway 17 is a duct 18 for supplying combustion-supporting air to the chamber 14 for delivery through the checkered wall into the combustion chamber, as will presently be described.

Located within each compartment of the

chamber 14 is a burner 19 comprising a manifold 20 to which a hydrocarbon fluid, such as oil or gas, may be delivered through a supply pipe 21, and nozzles 22 leading from the manifolds through the openings in the checkered wall 13 for delivering the hydrocarbon fuel into the combustion chamber for co-mingling with combustion-supporting air passing from the chamber 14 through the wall openings about the nozzles to provide a fuel mixture for combustion within the combustion chamber.

Opening from the upper rear corners of the heating or still chamber are horizontal flues 23 which extend through the walls of the furnace to the vertical flues 24 in extensions 25 of the furnace structure. The vertical flues 24 open to horizontal flues 26 in horizontal extensions 27 of the furnace structure and lead to a common stack 28.

Extending transversely beneath the furnace floor is a passageway or conduit 29, having upturned ends 30 communicating with fan housings 31, which in turn communicate through throats 32 with the horizontal flues 26, the fan housing being removably mounted on the extensions 27 and the throats 32 communicating with the upper portions of the flues 26. Fans 33 are rotatable in the housings 31 on shafts 34, journaled in bearings 35, 35' on the ends of the housings and on bases 36 supported by the extensions 27 and connected with motors 37, also mounted on said bases 36.

35 The passageway 29 has outlet through a checkered wall 38 into a trench 39 that opens through the furnace floor 5 at the rear end of the combustion chamber to deliver spent gases returned through the flues 23 across the line of flow of products of combustion passing through the combustion chamber to the heating chamber for recirculation through the heating chamber mixed with fresh products of combustion.

40 Located in the flues 26, between the ports 32 and the stack 28, are preheaters 40, preferably comprising closed, metallic housings 41 and tubes 42. Opening to one end of each housing 41 is a duct 43 for admitting fresh air to the housing about the tubes 42 and opening from the other end of the housing is the duct 18 through which such air after being heated by radiation from the tubes is delivered to the chamber 14 at the front end of the combustion chamber. Impeller fans 44 are provided for forcing air through the pre-heaters to the chamber 14 and thence to the combustion chamber.

45 Flow of gases from the horizontal stack flues 26 to the transverse passageway 29 is controlled by dampers 45 in the throats 32, leading to the fan housings 31 and by dampers 46 in the fan housings at the high pressure side of the fans, providing a double control of the spent gas supply to the furnace.

Flow of surplus gases to the stack outlet is controlled by dampers 47, one in each flue 26 between the relative preheater and the stack. Consequently separate control of supply of gases for recirculation and for stack outlet is provided for each of the flues 26 and its communicating fan housing, so that equalization of temperature at lateral extremes of the heating chamber may be effected.

I have illustrated the still employed in connection with the furnace as of tubular type, the tube bundle 48 extending from front to rear through the heating chamber at an inclination and communicating at its respective ends with drums 49 communicating with the tank 50 which is supported on the roof of the heating chamber. The furnace may comprise suitable sight openings and manholes and other equipment in accordance with ordinary practice but which will not be described in detail as they form no part of the present invention.

In the operation of a furnace constructed as described, the hydrocarbon element of a fuel mixture, such as oil or gas, is delivered through the burners into the combustion chamber and fresh air delivered through the ducts and preheaters into the air chamber and thence through the checkered wall about the burner nozzles for co-mingling with the hydrocarbon element to provide a combustible fuel mixture. This fuel mixture is ignited within the combustion chamber and substantially complete combustion produced in the chamber. Products of combustion thus produced are conducted into the heating chamber and pass in heating contact with the still, flowing between the tubes, if the still is of the type illustrated, and pass into the outlet flues at the upper rear corners of the heating chamber. Flowing through the outlet flues the spent gases pass through the flues leading to the outlet stack, some of the gases being drawn from the stack flues into the return passageway by suction from the circulating fans, under regulated control by the dampers in the flue throats and fan housings, and impelled through the conduit and through the checkered wall into the trench and from the trench across the line of flow of fresh products of combustion to the heating chamber. Upon delivery from the trench the spent gases co-mingle with the fresh products of combustion, forming a substantial volume of heating medium for recirculation through the heating chamber. The gases in contact with the still give up their heat to the still to vaporize contents of the still and upon return to the combustion chamber, temper the fresh products of combustion to avoid excessive heats in the still chamber and have their temperature restored to the proper degree by the fresh products of combustion. Surplus of the spent gases over the quantity required for maintaining a constant volume in the still

chamber, passes on through the stack flues to the preheaters and through the preheaters to the stack outlet, the gases passing through the preheaters at a temperature to condition the incoming fresh air for combustion in the furnace and the air so conditioned in turn raising the temperature of the hydrocarbon fuel element in the burners so that the latter reaches the combustion chamber at a temperature and in condition for readily comingling with the combustion-supporting air and tending to complete combustion of the mixture.

It is apparent from the foregoing that I have provided for recirculation of the medium for heating a still which is economical in the consumption of fuel and in upkeep of the furnace and still elements, in that excessive temperatures and deterioration by oxidation is obviated by promotion of combustion and dilution of any free oxygen that might otherwise affect the still in case of incomplete combustion.

What I claim and desire to secure by Letters Patent is:

1. A furnace of the character described, comprising communicating combustion and heating chambers, a flue leading from the heating chamber, a conduit extending transversely beneath the furnace floor and communicating with said flue, a trench parallel to and communicating with said conduit and opening through the furnace floor for delivering flue gases to the combustion chamber across the line of flow through the combustion chamber to the heating chamber for recirculating the flue gases through the heating chamber mixed with fresh products of combustion, and means for exhausting some of the flue gases to maintain the volume of flow through the heating chamber substantially constant.

2. A furnace of the character described, comprising communicating combustion and heating chambers, a flue leading from the heating chamber, a conduit communicating with said flue, a trench located beneath the level of the furnace floor in communication with said conduit and delivering flue gases upwardly through said floor across the line of flow through the combustion chamber to the heating chamber for recirculating the flue gases through the heating chamber mixed with fresh products of combustion, means for exhausting some of the flue gases to maintain the volume of flow through the heating chamber substantially constant, and means for promoting circulation of the gases.

3. In a furnace of the character described, a horizontal combustion chamber, a vertical heating chamber in open communication with one end of the combustion chamber, a trench arranged transversely beneath the furnace floor and opening to the combustion chamber through said floor, a flue opening from the

heating chamber at a point remote from the combustion chamber, a conduit leading from the flue to the trench, and means in said conduit for drawing gases from the flue and impelling them from the trench into the combustion chamber to mix the flue gases with fresh products of combustion for circulation through the heating chamber.

4. In a furnace of the character described, a combustion chamber having a horizontal floor and a heating chamber in open communication with the combustion chamber, a flue opening from the heating chamber, a conduit extending transversely adjacent the floor of the combustion chamber and communicating with said flue, a trench beneath the level of the furnace floor in communication with said conduit and opening transversely through said floor for delivering flue gases into said combustion chamber across the line of flow through the combustion chamber, and means for inducing flow of gases from the flue through the trench for recirculation through the heating chamber mixed with fresh products of combustion.

5. A furnace of the character described, comprising communicating combustion and heating chambers, an air chamber at the front end of the combustion chamber having a checkered wall opening to the combustion chamber, a manifold in the air chamber having branches leading through the openings in said wall for delivery into the combustion chamber, means for supplying fluid fuel to the manifold, means for impelling combustion-supporting air through the chamber and wall to the combustion chamber for co-miningling with said fuel medium to provide a combustible fuel mixture, and means conducting gases from the heating chamber and delivering the same to the combustion chamber across the line of flow of products of combustion through the combustion chamber to the heating chamber for recirculation through the heating chamber mixed with fresh products of combustion.

6. A furnace of the character described, comprising communicating combustion and heating chambers, an air chamber at the front end of the combustion chamber having a checkered wall providing communication between the air chamber and the combustion chamber, a burner in the air chamber having nozzles projecting through the wall openings for delivery into the combustion chamber, a flue leading from the heating chamber, a passageway opening from said flue and delivering into the combustion chamber across the line of flow of products of combustion for recirculation of flue gases through the heating chamber in combination with fresh products of combustion, a preheater in said flue, and means for impelling a flow of fresh air through the preheater and air chamber to the combustion chamber.

7. A furnace of the character described, comprising communicating combustion and heating chambers, a flue leading from the heating chamber, an air chamber at the front end of the combustion chamber comprising a checkered wall through which the air chamber communicates with the combustion chamber, a burner in said air chamber having nozzles extended through the checkered wall for delivery into the combustion chamber, a pre-heater in said flue, means for impelling fresh air through the preheater and air chamber to the combustion chamber, a passageway tapping the flue and comprising a trench opening 15 transversely through the floor of the furnace between the air chamber and heating chamber, and means in said passageway for drawing gases from the flue and impelling said gases across the line of flow of products of 20 combustion passing through the combustion chamber to the heating chamber for recirculating said gases through the heating chamber mixed with fresh products of combustion.

8. A furnace of the character described, comprising a horizontal combustion chamber and a vertical heating chamber in communication with the rear end of the combustion chamber, flues opening from opposite sides of the heating chamber at points remote from the combustion chamber, a passageway extending transversely beneath the combustion chamber and communicating with said flues at its opposite ends, a trench paralleling the passageway, opening through the floor of the furnace and a checkered wall for passing 30 gases from the passageway to the trench, fans in said passageway for drawing gases from the flues and impelling the same through the trench, preheaters in said flues between the passageway and said stack outlet, and means 35 for impelling fresh air through the preheaters and air chamber to the combustion chamber.

9. A furnace of the character described, comprising a horizontal combustion chamber and a vertical heating chamber communicating with the rear end of the combustion chamber, an air chamber at the front end of the combustion chamber divided vertically to 45 provide separate compartments, each compartment having a checkered wall through which communication is afforded with the combustion chamber, a burner in each of said compartments having nozzles extended 50 through the checkered walls for delivery into the combustion chamber, a trench arranged transversely of the combustion chamber and opening through the bottom thereof, flues leading from opposite sides of the heating 55 chamber, a passageway beneath the combustion chamber and communicating with said flues, a checkered wall separating the passageway from said trench, means for drawing 60 gases from said flues and impelling the same through said trench across the line of 65

flow of products of combustion through the combustion chamber for recirculation through the heating chamber mixed with fresh products of combustion, preheaters in said flues between the passageway and stack outlet, and means for conducting fresh air through the preheaters to the air chamber.

10. In a furnace of the class described, walls enclosing a chamber including a combustion zone and a heating chamber, a floor 75 extending inwardly from the front wall and constituting a floor of the combustion zone, a floor in the plane of the first-named floor extending rearwardly and constituting the floor of the heating chamber and downwardly 80 extending walls producing a recess between and beneath the level of said floors, one of said walls having apertures, and means delivering heated gases from the heating chamber through said apertures into the recess.

11. In a furnace structure, walls and an offset roof enclosing a chamber including a combustion zone and a heating chamber, and a floor having spaced parts and a recessed portion between and beneath the level of said parts, the rear wall of the recessed portion having apertures, and means delivering heated gases through said apertures to be baffled by the front wall of the recess and delivered upwardly through the recesses in the 95 floor into the heating zone.

12. A furnace of the character described, comprising a horizontal combustion chamber and a vertical heating chamber in communication with the rear end of the combustion chamber, flues opening from opposite sides of the heating chamber at points remote from the combustion chamber, a passageway extending transversely beneath the combustion chamber and communicating 100 with said flues at its opposite ends, a trench paralleling the passageway, opening through the floor of the furnace and a checkered wall for passing gases from the passageway to the trench, a fan at each end of the passageway 110 for drawing gases from a respective flue and impelling the same through the trench, a damper in each end of the passageway providing separate control of flow from the flues, preheaters in said flues between the passageway and said stack outlet, and means for impelling fresh air through the preheaters and air chamber to the combustion chamber.

13. A furnace of the character described, comprising a horizontal combustion chamber and a vertical heating chamber in communication with the rear end of the combustion chamber, flues opening from opposite sides of the heating chamber at points remote from the combustion chamber, a passageway extending transversely beneath the combustion chamber and communicating with said flues at its opposite ends, a trench paralleling the passageway, opening through the floor of the furnace and a checkered wall for passing 120

gases from the passageway to the trench, a fan at each end of the passageway for drawing gases from a respective flue and impelling the same through the trench, a damper in each end of the passageway providing separate control of flow from the flues, preheaters in said flues between the passageway and said stack outlet, means for impelling fresh air through the preheaters and air chamber to the combustion chamber, and a damper in each flue between the respective preheater and the chamber stack outlet.

14. A furnace of the character described comprising communicating combustion and heating chambers, a trench located below the level of the furnace floor and opening therethrough, a flue leading from the heating chamber, and a conduit opening from said flue and to said trench whereby flue gases are mixed with fresh products of combustion in the combustion chamber and recirculated through the heating chamber.

In testimony whereof I affix my signature.
WARD T. BARKER.
